SHIP ANCHOR

Paul W. Polenz, La Jolla, Calif.

Application September 29, 1950, Serial No. 187,557

3 Claims. (Cl. 114—208)

1

This invention relates to marine equipment, and more particularly to a ship anchor.

The object of the invention is to provide a ship anchor which will afford maximum holding power or resistance to dragging.

Another object of the invention is to provide a ship anchor which includes a novel locking mechanism which will not clog or become inoperative, due to entanglements with weeds, or other obstructions, the anchor being readily stored away when not being used.

Another object of the invention is to provide a ship anchor which is extremely simple and inexpensive to manufacture.

Other objects and advantages will be apparent during the course of the following description.

In the accompanying drawings forming a part of this application, in which like numerals are used to designate like parts throughout the same:

Figure 1 is a side elevational view of the anchor, constructed according to the present invention;

Figure 2 is a top plan view of the anchor of the present invention;

Figure 3 is an enlarged fragmentary side elevational view of the anchor, with one of the legs of the shank broken away to illustrate the parts therein;

Figure 4 is a sectional view taken on the line 4—4 of Figure 3;

Figure 5 is a top plan view of a modified form of the base plate that may be used with the assembly of Figure 1;

Figure 6 is a top plan view of another modified base plate;

Figure 7 is a view similar to Figure 3, but showing another modified anchor;

Figure 8 is a fragmentary side elevational view of another modified form of the invention and taken on the line 8—8 of Figure 10;

Figure 9 is a side elevational view of the anchor of Figure 8, with parts broken away and in section;

Figure 10 is a sectional view taken on the line 10—10 of Figure 9;

Figure 11 is a top plan view of another modified form of the invention;

Figure 12 is a sectional view taken on the line 12—12 of Figure 11;

Figure 13 is a sectional view taken on the line 13—13 of Figure 12;

Figure 14 is a side elevational view, with parts broken away and in section, of another modified form of the anchor;

2

Figure 15 is a sectional view taken on the line 15—15 of Figure 14.

Referring in detail to Figures 1 through 4 of the drawings, the numeral 30 designates a base plate which may be made of any suitable material, such as metal, the base plate 30 including an intermediate flat portion 31 that has projecting therefrom a pair of inclined flukes 32. The flukes 32 may be arranged opposite from each other, and the ends of the flukes 32 are provided with V-shaped notches 33, Figure 2. Also, the free ends of each of the flukes 32 are tapered, as at 34, Figure 1, such that when the anchor is being used, the flukes will dig into the mud at the bottom of the river or sea, so that the anchor will not accidentally move.

Projecting from opposite ends of the center portion 31 of the base plate 30 is a pair of tongues 35. The tongues 35 are preferably flat, and these tongues help to prevent the anchor or base plate from accidentally turning over, as when the boat shifts its position. Projecting upwardly from the base plate 30 and secured thereto in any suitable manner is a vertically disposed upright or center piece 36, Figure 1. The center piece 36 is provided with an arcuate slit 37, and portions of the slit 37 are arranged angularly with respect to the main portion thereof, the angular portions of the slit 37 being designated by the numerals 38.

Pivotedly connected to the center piece 36 is a shank or handle 39. The handle 39 has its lower end bifurcated so as to define a pair of spaced, parallel legs 40, and extending between the legs 40 and carried thereby is a pin 41. The pin 41 is adapted to be moved through the slit 37. As shown in Figure 3, the pin 41 can be positioned in one of the end angular portions 38 of the slit 37, so as to lock the shank 39 in its adjusted position. A pin 42 extends between the lower ends of the legs 40, the pin 42 extending through slots 43 which are arranged in each of the legs 40. The pin 42 also extends through the center piece 36, whereby a pivotal connection is provided between the shank 39 and the center piece 36.

From the foregoing it is apparent that an anchor has been provided wherein accidental turning over of the base plate will be prevented due to the tongues 35. Also, the wide flukes 32 having tapered ends 34, will dig into the mud or bottom of the sea when the anchor is moved so as to offer a maximum drag or resistance to movement of the anchor. Also, the shank 39 can be locked in its adjusted position by means of the pin 41. Thus, by arranging the shank 39

so that the pin 41 is seated in one of the end portions 38, accidental pivotal movement of the shank 39 will be prevented. When it is desired to pivot the shank 39, tension on the shank 39 is released so that the pin 41 can move out of the portion 38, whereby the shank can be pivoted. A suitable rope or cable can be attached to the shank 39 by means of a ring 44, Figure 1, the ring 44 being attached to the upper end of the shank 39.

In Figure 5, there is shown a modified base plate which is indicated by the numeral 45. The base plate 45 is adapted to be used in exactly the same manner as the base plate 30. The base plate 45 of Figure 5 includes a pair of oppositely extending tongues 46, and there are provided on each side of the base plate 45 a pair of flukes 47. The base plate 45 further includes an upstanding center piece 48. The tongues, flukes and center piece of the base plate 45 serve the same functions as those parts which have been previously described in connection with Figures 1 through 4.

Referring to Figure 6, there is shown another modified base plate which is indicated generally by the numeral 49. The base plate 49 includes a plurality of spaced, parallel flukes 50 which are relatively narrow in width. Also, the base plate 49 is provided with a pair of oppositely extending tongues 51 and a vertically disposed center piece 52, these parts also serving the same functions as the flukes, tongues and center piece of Figures 1 through 4.

Referring to Figure 7, there is shown a modified anchor which utilizes the base plate 30 and center piece 36 of Figures 1 through 4. In the assembly shown in Figure 7, the shank is indicated by the numeral 53 and has substantially the same construction and use as the shank 39. However, the shank 53 includes a pair of spaced, parallel, lower legs 54 which straddle the center piece 36. The legs 54 carry the usual or same pin 41, the pin 41 projecting through the slit 37. The pin 42 which effects the pivotal connection between the legs 54 and the center piece 36 extends through open-ended slots 55 which are arranged in the bottom of the legs 54. Pins 29 project from center piece 36 for engagement with legs 54.

Referring to Figures 8, 9 and 10 of the drawings, there is shown another modified ship anchor, wherein the base plate is indicated generally by the numeral 56. The base plate 56 includes the flukes 57, and extending upwardly from the base plate is the center piece 58. Arranged along the upper edge of the center piece 58 and secured thereto in any suitable manner is a wedge 59, there being one of the wedges 59 arranged along each side of the center piece 58. The wedge 59 is provided with an arcuate lower surface 62, Figure 8, and extending through the center piece 58 is a pair of spaced, parallel, locking pins 60 and 61.

Pivottally connected to the center piece 58 is a shank 63. The shank 63 is provided with a pair of spaced, parallel legs 64 on its lower end, and the legs 64 straddle the center piece 58. Each of the legs 64 carries a pin 65 which is adapted to engage with the lower surface of the wedge 59. Projecting from opposite sides of each of the legs 64 is a pair of ears 66, Figure 8, and the ears 66 are adapted to engage one of the locking pins 60 or 61 so as to help prevent accidental pivotal movement of the shank 63.

The lower end of each of the legs 64 is cut 75

away to define a slot 67, and a pin 68 projects through the registering slots 67 and through the center piece 58. The pin 68 thus provides a pivotal connection between the shank 63 and the center piece 58.

The anchor shown in Figures 8 through 10 thus can be arranged so that the shank 63 is in the position shown in Figure 8, or by releasing tension on the line to which the shank is attached, the shank can be arranged in the position shown in Figure 9. Or, if desired, the shank 63 can be moved to a position so that the pin 60 is engaged by one of the ears 66. The anchor will prevent accidental movement of the boat and can thus be locked in any desired position.

Referring to Figures 11, 12 and 13, there is shown another modified ship anchor, wherein the base plate is designated by the numeral 68'. Extending from the base plate 68' are the flukes 69, and projecting upwardly from the base plate 68' is a pair of vertically disposed, spaced, parallel center pieces 70, Figure 13. Extending between the pair of center pieces 70 and secured thereto in any suitable manner is a pair of spaced, parallel pins 71 and 72, and also extending between the pairs of center pieces 70 is a circular rod 73.

Pivottally connected to the base plate is the shank 74. Secured to opposite sides of the shank 74 adjacent its lower end is a pair of legs 75, the legs 75 straddling the bar or rod 73 so that a pivotal connection is effected between the shank 74 and the base plate. A T-shaped cross piece 76, Figure 12, is secured to the lower ends of the legs 75. Carried by the shank 74 is a locking pin 77, Figure 13, and the locking pin 77 is adapted to engage the lower surface of the wedges 71'. It will be seen from Figure 12 that the shank 74 can be arranged so that the locking pin 77 engages the lower end portions of the wedges 71', while at the same time one of the legs 75 abuts the pin 72. Thus, accidental pivotal movement of the shank 74 will be prevented. When it is desired to move the shank 74 to a different position, tension on the cable or line to which the shank 74 is attached is released, whereby the shank 74 can be moved toward the pin 73 so that the pin 77 can slide beneath the wedges 71' until the shank 74 is moved to the desired location.

Referring to Figures 14 and 15 of the drawings, there is shown another modified ship anchor which includes a pair of spaced, parallel, vertically disposed center pieces 79, the base plate being indicated by the numeral 78. Extending between the upper ends of the center pieces 79 are suitable spaced, parallel braces 80, the braces 80 serving to maintain the center pieces in their proper spaced relation. A shank 81 is pivottally connected between the pair of center pieces 79. For effecting the pivotal connection between the shank 81 and the base plate 78, a roller 82 is mounted on a shaft 83, the shaft 83 being rotatably supported between center pieces 79. A crossbar 84 is secured to the lower ends of the shank 81, and the shank 81 extends through registering slots in the roller 82 and shaft 83. The crossbar 84 is adapted to be seated or received in registering cutouts 85 or 86 which are arranged in the lower surfaces of the center pieces 79. When the crossbar 84 is seated in the cutouts 85 or 86, accidental pivotal movement of the shank 81 is prevented. To disengage the crossbar from the cutouts, the tension on the cable to which the shank is attached is released.

Suitable flukes 87 extend from the upper surfaces of the cross pieces 79, and when the anchor is being used, the flukes 87 will dig into the mud to thereby prevent shifting movement of the anchor.

From the foregoing it is apparent that an anchor has been provided wherein accidental overturning of the anchor will be prevented, and also, the anchor is constructed so that a maximum amount of drag or resistance is provided. The shank can be pivoted or adjusted to various angles relative to the base plate. The locking means embodied in the anchor of the present invention will insure that the shank does not accidentally move from its adjusted position.

The locking mechanism of the ship anchor of the present invention can be readily disengaged. Since flukes extend from opposite ends of the base plate, the anchor is provided with twice the ordinary holding power. Also, there is sufficient clearance between parts of the lock so that weeds or other objects will not accidentally become entangled therein and prevent operation of the anchor.

I claim:

1. A ship anchor comprising a base plate, a plurality of flukes extending from opposite sides of said base plate, a tongue projecting from each end of said base plate, a vertically disposed center piece projecting upwardly from said base plate and secured thereto, there being an arcuate slit arranged in said center piece, portions of said slit being arranged angularly with respect to the main portion thereof, a shank having a bifurcated end defining spaced legs straddling said center piece, there being registering slots in said legs, a pivot pin extending through said slots and through said center piece, and a pin carried by said legs and extending through said slits.

2. An anchor comprising a base plate, a plurality of flukes extending from said base plate, a tongue projecting from each end of said base plate, a center piece projecting upwardly from

said base plate and secured thereto, there being an arcuate slit arranged in said center piece, portions of said slit being arranged angularly with respect to the main portion thereof, a shank having a bifurcated end defining spaced legs straddling said center piece, there being registering slots in said legs, a pivot pin extending through said slots and through said center piece, and a pin carried by said legs and extending through said slit.

3. An anchor comprising a base plate, a plurality of flukes extending from said base plate, a tongue projecting from each end of said base plate, a center piece projecting upwardly from said base plate and secured thereto, there being a slit arranged in said center piece, portions of said slit being arranged angularly with respect to the main portion thereof, a shank having spaced legs straddling said center piece, there being registering slots in said legs, a pivot pin extending through said slots and through said center piece, and a pin carried by said legs and extending through said slit.

PAUL W. POLENZ.
